UNITED STATES PATENT OFFICE.

RICHARD SPRINGE, OF LEAVENWORTH, KANSAS.

LEGGING.

1,115,611.

Specification of Letters Patent.

Patented Nov. 3, 1914.

Application filed July 27, 1914. Serial No. 853,523.

To all whom it may concern:

Be it known that I, RICHARD SPRINGE, a citizen of the United States, residing at Leavenworth, in the county of Leavenworth 5 and State of Kansas, have invented or discovered certain new and useful Improvements in Leggings, of which the following is a specification, reference being had therein to the accompanying drawing.

10 This invention relates to that class of leggings covered by U. S. Patents Nos. 899,590 and 966,525, and comprising a forked fastening strap the single part of which is adapted to engage a buckle located at a 15 point not far from the middle of the legging, so that only a single strap need be manipulated in fastening or unfastening the legging.

The present improved legging comprises 20 a strap one end of which is attached to one edge of the piece of leather or other suitable material constituting the body of the legging at or near either the top or bottom of said edge, and the other end of which strap is provided with a suitable fastening device, and a second and longer strap one end of which is attached to the edge of said body near either the top or bottom of said edge, the said straps being so disposed as to converge and come together at said fastening device, said longer strap then extending to a buckle or other fastening located between the ends of the body of the legging and being provided near its free end with a series 35 of holes so as to permit it to be adjustably engaged with said buckle or fastening device. As the two straps thus come together at the first-mentioned fastening device they constitute what is practically a forked strap; 40 and as the said first-mentioned fastening device is adapted to afford an adjustable connection of the said straps at their converging point this improved construction provides means whereby, by a single adjustment, the two straps constituting practically a forked strap, may be lengthened or shortened, as will hereinafter more fully appear.

In the accompanying drawing Figure 1 is 50 a perspective view of the improved legging. Fig. 2 is a detail view showing the portions of the two straps and the buckle at which the two straps come together, and which affords an adjustable connection for said straps at their converging point. Fig. 3 is a section through the parts shown in Fig. 2, and Fig. 4 is a detail view of a preferred

form of buckle with which both straps are connected.

Referring to the drawing, 12 denotes a piece of leather, canvas, or other suitable material, which is to constitute the body of the legging, and which may have a suitable lining, if desired. To one edge of the overlapping part of the body of the legging, preferably near the top of said edge, as at 13, is secured one end of a strap 14 to the other end of which is attached a buckle 15. Said buckle 15 is preferably of the form most clearly shown in Fig. 4 in that it comprises a cross bar 16 provided with a stud 17, 60 and the end bar of said buckle to which the strap 14 is attached being preferably inclined with reference to the side bars of said buckle, for a purpose which will hereinafter appear. 75

To the overlapping edge of the body of the legging, preferably near the bottom of said edge, as at 18, is attached a second and longer strap 19 which is adapted to pass around the body of the legging and through the buckle 15, said strap being adapted to be adjustably attached to the said buckle so that it may be lengthened or shortened at its meeting point with the strap 14. To this end, in the construction herein shown, the 80 said strap 19 is provided at the portion thereof adjacent the said buckle 15 with a series of holes 20 any one of which may be engaged by the stud 17 on the cross bar 16 of the said buckle, as more clearly shown in 85 Figs. 2 and 3. From the buckle 15 the strap 19 runs through a wire loop 21 attached to the underlying part of the body of the legging and passing through one or the other of two slots 22 formed in the overlapping part of the body of the legging and affording an adjustable connection between the edges of the body of the legging, the 90 said strap passing from said wire loop 20 through a buckle, as 23, secured to the body 95 of the legging as in the patents above referred to, and to which buckle the end of the said strap may be adjustably secured by virtue of a series of holes 24 formed near the free end of the strap. By forming the end 100 bar of the buckle to which the strap portion is attached at an incline, as shown, the said buckle is better adapted to be so disposed as to receive the two straps converging at said buckle without distorting the said 105 straps, thereby permitting the latter to lie smoothly on the outside of the legging. 110

From the foregoing it will be apparent that the present improved construction affords all of the advantages of the forked strap construction of Patents Nos. 899,590 5 and 966,525, hereinbefore referred to, while said improved construction presents the additional advantage of affording an adjustment of the two straps at their converging point, so that, by a single adjustment, the two 10 straps, affording practically a forked strap, may be lengthened or shortened to better adapt the legging to different persons.

While the drawing shows the strap which carries the buckle as being attached to the 15 edge of the overlapping part of the body of the legging near the top thereof, and the other strap as being attached to the edge of the overlapping part of the body of the legging, near the bottom of said edge, it will 20 be understood that this arrangement might be reversed without departing from the essence of the invention; nor is the invention to be understood as being limited to the particular fastening device at the converging 25 point of the straps afforded by the buckle 15, as a differently constructed fastening device or buckle, which would afford an adjustable connection of the two straps at their converging point, might be employed 30 without departing from the spirit of the invention.

Having thus described my invention I claim and desire to secure by Letters Patent:

1. A legging comprising a piece of suitable material one edge of which is adapted to overlap the other, a strap attached at one end to said overlapping edge near one end of the latter, a second strap attached at one end to said overlapping edge near the other 40 end of said edge, said strap being longer than the first-named strap, said straps being so disposed as to converge and come together between the ends of said second strap, a fastening device located at the converging point of said straps and adapted to afford a lengthening and shortening adjustment at 45 said point, and a suitable fastening device attached to the body of the legging for securing the free end of the said second strap.

50 2. A legging comprising a piece of suit-

able material one edge of which is adapted to overlap the other, a strap attached at one end to said overlapping edge near one end of the latter, a second strap attached at one end to said overlapping edge near the other end of said edge, said strap being longer than the first-named strap, said straps being so disposed as to converge and come together between the ends of the said second strap, a fastening device located at the converging point of said straps and adapted to afford a lengthening and shortening adjustment at said point, and a suitable fastening device attached to the body of the legging for securing the free end of the said second strap, said first-mentioned fastening device consisting of a buckle having a cross-bar provided with a stud, and the said second strap being provided with a series of holes whereby it may be adjustably connected with said stud.

3. A legging comprising a piece of suitable material one edge of which is adapted to overlap the other, a strap attached at one end to said overlapping edge near one end of the latter, a second strap attached at one end to said overlapping edge near the other end of said edge, said strap being longer than the first-named strap, said straps being so disposed as to converge and come together between the ends of the said strap, a fastening device located at the converging point of said straps and adapted to afford a lengthening and shortening adjustment at 75 said point, a suitable fastening device attached to the body of the legging for securing the free end of the said second strap, said fastening device consisting of a buckle having a cross-bar provided with a stud, and an inclined end bar for the attachment 80 of said first-named strap, and the said second strap being provided with a series of holes whereby it may be adjustably connected with said stud.

In testimony whereof I affix my signature, 95 in presence of two witnesses.

RICHARD SPRINGE.
